United States Patent Office

Des. 185,268

Patented May 26, 1959

185,268

PLASTIC SHEET MATERIAL

John R. Ellefson, Newburgh, N.Y., assignor to E. I. du Pont de Nemours and Company, Wilmington, Del., a corporation of Delaware

Application February 6, 1959, Serial No. 54,488

Term of patent 14 years

(Cl. D87—3)

FIG. 1

FIG. 2

FIG. 3

Figure 1 of the drawing is a plan view of my new design showing the repeating unit within the heavy broken lines. Figure 2 is a cross sectional view taken on line 2—2. Figure 3 is a cross-sectional view taken on line 3—3.

I claim:

The ornamental design for a plastic sheet material, substantially as shown.
